ROOF AND SIDE WALL CONNECTION FOR
RAILWAY CARS AND SIMILAR VEHICLESAlbert G. Dean, Narberth, Pa., assignor to The
Budd Company, Philadelphia, Pa., a corpora-
tion of Pennsylvania

Application October 24, 1947, Serial No. 782,004

8 Claims. (Cl. 105—397)

1

The invention relates to a connection between the lateral margins of a roof and the upper margins of the side walls of railway cars and similar vehicle bodies. More specifically, the invention relates to a reinforcement of side wall and roof in the regions where the two meet.

The outstanding objects of the invention are a side wall and roof construction for railway cars and similar vehicles which is light in weight and simpler in construction than corresponding previous designs while giving ample strength to the trusswork represented by the vehicle body in its entirety.

With the above objects in view, the invention provides a shear panel in the region where roof and side walls meet, which shear panel reinforces the margins of the roof sheathing, constitutes part of the connecting means between roof and side wall, interconnects the upper ends of the side wall posts, forms part of an upper chord structure for the side wall truss, and is strengthened along its lower margin by an outwardly projecting upwardly facing channel adapted to serve simultaneously as a drain channel.

The invention and its details, as well as further objects and advantages thereof, will be more easily and clearly understood from the embodiment illustrated in the attached drawing and described hereinafter.

In the drawing:

Figure 1 is a small-scale side elevation of a railway car;

Figure 2 is a fragmentary side elevation of the roof in the region of one of the side door openings;

Figure 3 is a fragmentary sectional inside perspective of the connecting zone between roof and one side wall, the section being taken along line 3—3 of Figure 1; and

Figure 4 is a fragmentary section along line 4—4 of Figure 2 on the scale of Figure 3.

The illustrated body has side walls S and a roof R. Windows W and doors D are provided in the body sides. While the drawing shows and the following description refers mostly to the construction on one side of the body, there are, of course, two side walls and longitudinal roof margins which may have substantially the same construction.

The illustrated side wall structure comprises longitudinally spaced vertical posts 10 in the form of U- or Z-sections. One of such posts is arranged along each vertical margin of the door and window openings. Adjoining posts are con-

2

nected between successive door and window openings by shear panels 11 and they are interconnected between the door openings by profiles 12 extending from post to post and secured with them. Along the upper margins of the window openings, between such window openings and between the window openings and the door openings, the posts are, furthermore, interconnected on their insides by a chord member in the form of a sheet metal profile 13.

If the side wall is pre-assembled as a sub-unit before its connection to the roof, the upper ends 14 of the posts project freely above the upper margins of the panels 11, profiles 12 and chord member 13. A gusset plate 15 at the inside of the upper end of each or most of the posts may constitute part of the side wall sub-assembly unit.

The roof R comprises longitudinally spaced and transversely arched carlines 16, the ends of which fit telescopingly and are secured in a U-section marginal chord member 17, which member preferably extends over the entire length of the car and is arranged at the height of the top margins of the door openings. The carlines have longitudinally extending inner and outer flanges 18 and 19 which serve for the aforesaid securing to the walls of the channel section 17. The outer arm 18 of each carline 16 is attached to the inside of longitudinally corrugated roof sheathing 20 extending over the entire length of the car forming with the other roof elements a deep transversely arched truss. The roof sheathing 20 is also secured to the outside wall of the chord member 17.

An extension 21 of the roof sheathing projects downwardly beyond the member 17. The lower marginal portion of the extension 21 is reinforced and stiffened by a flat web 22 in the form of a narrow elongated strip extending uninterruptedly in longitudinal direction between consecutive door openings or between a door opening and the end of the car. This strip 22 projects downwardly beyond the lower margin of the roof sheathing extension 21 and is formed at its lower margin into an upwardly facing channel 23. The channel portions 23 not ending at an end wall are provided with drain holes 23, between window openings or at other unobjectionable places. The web is secured to the bottoms of the corrugations of the roof extension 21 preferably by electric spot welding.

At the location of each or most of the carlines a gusset plate 24 is interposed between and secured to the outer arms 18, carlines 16, and the

roof sheathing 20. Gusset 24 extends, furthermore, between the chord member 17 and the roof sheathing and overlaps part of the inside surface of the web 22 to which it is likewise secured, preferably by electric spot welding.

Above the door openings the extension 21 of the roof sheathing and the reinforcing web 22 with its channel 23 are cut out. In these regions the roof sheathing above the chord member 17 is reinforced by a web or panel 25 overlapping with its projecting marginal portion the outside wall of the chord member 17 and having an outwardly directed flange 26 secured to an angle member 27 which, together with the flange and the margin of the panel 25, forms an uninterrupted continuation of the channel 23. In addition, the structure around the upper portion of the door opening is reinforced by members 28.

If the roof is pre-assembled as a sub-unit before its connection to the side walls, then such sub-unit comprises the described carlines 16, chord members 17, roof sheathing 20 with extensions 21, webs 22 with channels 23, webs 25 with channels 26, 27, gussets 24, and reinforcements 28.

In final assembly, the roof overlaps with its downward extensions 21, its webs 22 and the lower portions of its gussets 24, the outsides of the upper ends of the side wall posts 14 and of the margins of the shear panels 11 and longitudinal profiles 12. On the other hand, the upwardly projecting portions of the gussets 15 on the side wall posts overlap the insides of the carlines 19. Along all the regions of overlap, the two units are connected with each other, again preferably by means of electric spot welding. Further angle brackets, not shown, may connect the transverse webs of the side wall posts 14 to the bottom walls of the channel section roof chord members 17.

The webs 22 and 25 not only reinforce the lower margin of the roof extension but constitute also effective connecting elements between the roof and side walls and, in addition, present drain pipes to keep rain water away from the door and window openings. In the completed car structure, the webs 22 are located opposite the profiles 13 of the side walls, resulting in a balanced construction; these elements, together with the profiles 12, resulting, furthermore, in longitudinal beams of considerable strength.

All members of the illustrated construction are formed of sheet metal, preferably of the high-tensile variety, for instance, of cold-worked austenitic stainless steel. Most of the connections between the different members are preferably made by means of electric spot welds which at many places in the drawing are shown in conventional manner.

The disclosed construction has great strength, is simple and of relatively light weight. Also, the assembly of the parts into the roof and side wall units as well as the connection of the units with each other is easy and convenient on account of the accessibility of the points of connection.

While one embodiment of the invention is disclosed, it should be understood that modifications and adaptations will easily occur to those skilled in the art, and that protection is sought for the invention as covered by the language and the spirit of the attached claims.

What is claimed is:

1. In a roof for railway cars and similar vehicles, longitudinally spaced and transversely

arched carlines interconnected by a sheet metal roof sheathing and by marginal rails, said roof sheathing extending downwardly beyond the carlines and said marginal rails to form part of final assembly means with the adjoining upper marginal portions of the body side walls, the lower margin of the downwardly projecting portions of the roof sheathing being reinforced on each side of the car by a continuous vertical web secured to the inner surface of the sheathing and projecting downwardly therebeyond, the downwardly projecting portions of said web being stiffened by its formation into an upwardly facing channel adapted for the reception and disposal of water from the roof.

2. In a roof for railway cars and similar vehicles, longitudinally spaced and transversely arched carlines interconnected by a longitudinally corrugated sheet metal roof sheathing and by marginal rails, said roof sheathing extending downwardly beyond the carlines and said marginal rails to form part of final assembly means with the adjoining upper marginal portions of the body side walls, the downwardly projecting portions of the roof sheathing being reinforced on each side of the car below said marginal rail by a continuous vertical web secured to the inner surface of the sheathing and projecting downwardly therebeyond, the downwardly projecting portion of said web being stiffened by its formation into an upwardly facing channel.

3. In a body structure for railway cars and similar vehicles, side wall trusses comprising longitudinally spaced vertical posts, a roof truss having longitudinally spaced transversely extending arched carlines lining up with at least certain of said posts, a longitudinally extending rail on each side of the body where the carlines and the posts meet, a longitudinally corrugated roof sheathing connected with the carlines and the marginal rails and having portions projecting downwardly beyond the carlines, and the rails, said portions of the sheathing being overlappingly connected to the outsides of the upper ends of the posts, gusset plates interposed between the roof sheathing and its downward extensions on the one hand, and the lower ends and the upper ends of carlines and posts respectively, on the other hand, further gussets extending across said rails and overlappingly secured to the inside of the carlines and posts, a longitudinally extending plane web on each side of the roof arranged at a distance below the respective rail and secured to the lower marginal region of the downwardly projecting portion of the corrugated roof sheathing and also secured to the outside of the posts so as to form with said roof extension and said rail a strong upper chord member for the side wall truss, and another longitudinal web secured to the inside of the posts at about the height of said first-named web.

4. In a body of railway cars and similar vehicles, a roof, a side wall, a door opening in one of the side walls, longitudinally spaced and transversely arched roof carlines interconnected by a sheet metal roof sheathing and by marginal rails, said roof sheathing extending downwardly beyond the carlines and said marginal rails forming part of final assembly means with the adjoining upper marginal portions of the body side walls, the lower margin of the downwardly projecting portions of the roof sheathing being reinforced on each side of the car by a continuous vertical web secured to the inner surface of the

sheathing and projecting downwardly therebeyond, the downwardly projecting portions of said web being stiffened by its formation into an upwardly facing channel which may simultaneously serve for the reception and disposal of water from the roof, said door opening extending upwardly to a point above the lower margin of the adjoining roof extension and its reinforcing web, a continuation of said web and of the channel formed along its lower margin extending around the upper portion of the door opening.

5. A body for railway cars and similar vehicles comprising a preassembled side wall unit and a preassembled roof unit connected with each other in final assembly; said side wall unit having a plurality of longitudinally spaced posts and means longitudinally interconnecting said posts, said means terminating at a distance below the upper ends of said posts so that end portions of the posts project upwardly beyond said means; said roof unit having longitudinally spaced carlines, a side rail connecting the ends of the carlines and roof sheathing covering and connected with said carlines and rail and provided with a marginal portion extending downwardly beyond said rail; said downwardly extending portion of said roof unit being secured in final assembly to the outside of said end portions of the posts above the means of the side wall unit interconnecting said posts and said downwardly extending portion having its lower margin connected to the upper margin of said means; and gusset plates overlappingly connected on the inside to the upper ends of said posts and to said roof rail.

6. A body for railway cars and similar vehicles comprising a pair of preassembled side wall units and a preassembled roof unit connected with each other in final assembly; each of said side wall units having a plurality of longitudinally spaced posts and means longitudinally interconnecting said posts, said means terminating in a chord structure arranged at a distance below the upper ends of said posts so that end portions of the posts project upwardly beyond said chord structure; said roof unit having longitudinally spaced carlines, side rails connecting the ends of the carlines and roof sheathing covering and connected with said carlines and rails and provided with marginal portions projecting downwardly beyond said rails; said downwardly projecting portions of said roof sheathing being secured in final assembly to the outsides of said end portions of the posts projecting beyond said upper chord structures of the side wall units and having their lower margins connected to said chord structures; and means extending on the inside across the space between said posts and said rails and being overlappingly secured to both.

7. A body for railway cars and similar vehicles comprising a pair of preassembled side wall units and a preassembled roof unit connected with each other in final assembly; each of said side wall units having a plurality of longitudinally spaced posts and means longitudinally interconnecting

said posts, said means terminating in a chord structure arranged at a distance below the upper ends of said posts so that end portions of the posts project upwardly beyond said means, said 5 side wall units having furthermore gusset plates secured to the insides of the posts and projecting upwardly beyond the ends thereof; said roof unit having longitudinally spaced carlines and side rails of upwardly facing channel shape telescopically fitted over and connected to the ends of the carlines, said roof unit having furthermore a roof sheathing covering and connected with said carlines and rails and provided with marginal portions extending downwardly beyond said rails; 10 said downwardly extending portions of said roof unit being secured in final assembly of roof and side wall units to the outsides of said end portions of the posts and having their lower margins connected to said chord structures, and said gusset plates extending across the space between said posts and said rails and being overlappingly secured in final assembly to the inner walls of said rails.

15 8. In a body for railway cars and similar vehicles, side wall trusses and a roof truss, said side wall trusses comprising longitudinally spaced vertical posts longitudinally interconnected by chord structures arranged at a distance below the upper ends of the posts, said roof truss comprising longitudinally spaced transversely extending arched carlines and a longitudinally corrugated roof sheathing connected with the carlines and terminating at a distance above said chord structures of the side wall trusses, a longitudinally extending rail on each side of the body between the 20 ends of carlines and posts, a continuous longitudinally extending plane web on each side of the body having its upper marginal portion overlapped by and secured to the roof sheathing, being connected to the said chord structure of the respective side wall truss.
